To all whom it may concern:

Be it known that I, Louis Marx, a citizen of and
the United States, and a resident of the city,
county, and State of New York, have invented
a new, original, and ornamental Design for a
Toy Locomotive, of which the following is a
specification, reference being had to the ac-
companying drawing, forming a part thereof,
wherein:

Fig. 1 is a side elevation of the toy locomotive;

and Fig. 2 is a plan view thereof.

I claim:

The ornamental design for a toy locomotive
substantially as shown.

LOUIS MARX.
